HEEL-SHAPING MACHINE

Clayton Straw, Henniker, N. H., assignor to Heel Finisher, Inc., Boston, Mass., a corporation of Massachusetts

Application May 13, 1939, Serial No. 273,442

17 Claims. (Cl. 12—87)

This invention relates to machines for cutting or trimming previously built-up heel blanks into finished form, and has as its object to provide an improved machine of this type capable of cutting heel blanks made of leatherboard smoothly and accurately into finished form. Additionally, the invention aims to provide such a machine which may be run by unskilled labor with safety and with a minimum of physical exertion, at a rapid rate of production of high-quality heels, so that substantial economy will be effected while producing a superior article. Further aims are to increase and facilitate the adaptability of the machine to the making of heels of different sizes, heights, shapes, and patterns, and to increase the safety and accuracy of operation of the machine.

Other objects of the invention, and the manner of attainment of these and the stated aims of the invention, are as made plain hereinafter.

An illustrative embodiment of the machine is shown in the accompanying drawings, in which:

Fig. 1 is a side elevation, omitting the timing mechanism, which is shown in Figs. 8 to 14.

Fig. 2 is a plan view.

Fig. 3 is a view in side elevation of certain parts connected with the turret, showing the means for rotating the heel on a vertical axis during the cutting.

Fig. 4 is a fragmentary elevation showing details of the track on which the heel-spindles travel from loading to working position.

Fig. 5 shows in elevation, and Fig. 6 in plan, certain details of construction of the individual heel-spindles carried by the turret.

Fig. 7 is a detail showing in vertical section on line 7—7 of Fig. 2 the movable mounting of the cutter and motor table.

Fig. 8 shows the mechanism for automatically driving the various parts of the machine in the proper timed relation to each other.

Fig. 9 is a vertical section on line 9—9 of Fig. 8.

Fig. 10 is a view in vertical section on line 10—10 of Fig. 8.

Fig. 11 is a vertical section partly on line 9—9 and partly on line 10—10 of Fig. 8.

Figs. 12, 13 and 14, are details of the mechanism of Fig. 8.

Figs. 15 and 16 are side elevation and plan views respectively showing one type of the heel on the work-support, illustrating the relation of the cutter blade, the blade being lower in its stroke in Fig. 16.

Fig. 17 is a side elevation of a different type of heel, showing its relation to the cutter blade.

Fig. 18 shows a special cam used to make fancy heels.

Fig. 19 shows in perspective the type of fancy heels made by the use of the cam of Fig. 18.

Fig. 20 is a bottom view of the fancy heel of Fig. 19.

The present machine employs the principle of the turret head carrying a plurality of work-supports successively propelled and manipulated by an automatic indexing mechanism into a plurality of locations or stations where successive operations are performed on the heel.

The heel-blank 1 on which the machine operates comprises lifts of leatherboard with rectangular edges and of successively increased area, glued, pressed, and nailed together to have a shape approximating closely the shape to be given the finished heel, but slightly larger at all points on its sides to allow for cutting to shape. The end of the heel which is to be seated against the shoe is cupped, while the tread surface is plane, and before being presented to the present machine the breast of the heel-blank has been given its usual concave shape by a trimming operation. The tread end is customarily provided with a leather or rubber tread lift, and preferably a top lift of harder material such as fiberboard is used on the cupped end.

30 The heel-blank 1 is placed on the heel-support or turn-table 3 of one of the plurality of heel-spindles mounted on rotating turret 4, numbering two in the present machine, while such turn-table occupies a position at the front or right-hand end of the machine as shown in Figs. 1 and 2, well away from the cutter. The cupped end of the heel-blank is applied to an aluminum plate 5 forming the slanting surface of the turn-table, with its breast pressed against a breast-gauge 7 and one side pressed against a rearwardly-extending gauge-finger 9, momentarily

35 swung into heel-engaging position by means of its supporting arm 11 pivoted at 13 on a bracket in connection with the turret. If necessary, a sheet of paper or other suitable material may be interposed between the heel and plate 5 to assist in cutting the fiberboard lift cleanly and without feather edges. The presser 15 is then brought down by raising handle 17 to clamp the heel-blank against the surface of plate 5, impaling it securely on short pins 12, whereupon foot treadle 21 is depressed, causing the indexing mechanism to be put in driving engagement with constantly rotating motor 23, whereby turret 4 is rotated on a fixed axis through 180° and

stopped. This brings the heel-blank on its turn-table into a fixed position in range of constantly rotating cutter 25, whereupon the indexing mechanism rotates the heel-blank one complete turn about a separate vertical axis extending through the heel, and simultaneously effects the movement of table 21 carrying the cutter 25 and motor 23 toward and from the heel-blank, while also lifting and lowering the turret, so that the sides of the heel-blank are trimmed into the desired shape and profile. At the completion of the cutting operation, the indexing mechanism comes to rest, and a second pressure upon foot treadle 21 again starts the indexing mechanism on its cycle, automatically rotating the turret through one-half turn, bringing the other turn-table or work-support and a new heel-blank placed thereon by the operator during the described cutting operation into position to be operated on by the cutter, the operator thereupon replacing the previously trimmed heel by a new blank, and so on throughout the continued operation of the machine.

To render the operation of shaping the heels fully automatic, thus requiring only the services of unskilled labor to feed the machine, the indexing, timing and controlling mechanism of Fig. 8 is employed, mainly located on a shelf 29 mounted within frame 31 of the machine below the working parts already described. To drive this mechanism, constantly running motor 23 imparts continuous rotation to a longitudinal countershaft 33 by means of jackshaft 35, intervening bevel gears 37, 39, pulley 41 and V-belt 43 driven by a pulley fixed on the motor shaft.

To rotate the turret in a clockwise direction, a longitudinal shaft 45 is constantly driven from countershaft 33 by means of intervening chain 47 and appropriate sprockets fixed on the respective shafts, and is coupled to a co-aligned shaft 49 through a single-revolution clutch 51 of known and standard design having a control-sleeve 53 at one end which is held from rotation by engagement, with a shoulder thereon, of one end of a lever 55, Figs. 9 and 11, mounted in rocking relation free on a shaft 51 and equipped near its other end with a shoulder 59. This shoulder is adapted to be engaged by a shoulder 61 on a vertical push-rod 63 connected through an arm 65 with a rockshaft 67 on which the foot treadle 21 is also fixed. Whenever the foot treadle is depressed, the release of control-sleeve 53 by lever 55 causes clutch 51 to drive shaft 49 in unison with shaft 45, thus rotating a vertical shaft 69 through appropriate bevel gears, and causing a spur gear 71 on the upper end of shaft 69 and engaging with an internal gear 73 at the bottom edge of the bell or skirt of the turret, to rotate the turret throughout 180° and thus bring the heel-blank supports successively into working relation with the cutter 25. Locking means for the turret has not been found necessary, but means for thus positioning and holding the turret in the desired angular position can easily be supplied.

To hold lever 55 out of engagement with control-sleeve 53 long enough to permit the clutch 51 and shaft 49 to make the necessary number of turns to bring the new heel-blank into working relation with the cutter by rotation of the turret head, a counter 75, Fig. 11, is mounted on a jackshaft 71 driven from periodically rotated shaft 49 by intermeshing spur gears 81, 79, respectively fixed to these two shafts, having the proper ratio to impart exactly one full rotation 75

to shaft 71 while the turret is moving. The full-diameter periphery of counter 75 engages a dog 83 fixed to lever 55 as soon as shaft 49 commences to rotate, thus holding the lever depressed until the notch in the rim of counter 75 has made a complete circuit and is again in position to receive dog 83, pull-spring 85 then rocking the lever to cause its end to engage the shoulder on control-sleeve 53 and throw out the clutch. During this rotation of the counter, shaft 49 has made the necessary number of rotations to impart a half turn to the turret. Appropriate change is made in the ratio of gears 79, 81, where three, four, or more, work-supports are employed about the turret.

To start the necessary relative movements of the heel-blank and the cutter after the blank has been brought into working position by the half-turn of the turret head just described, while guarding against premature commencement of these operations, a delayed-action clutch-release 87 is mounted on shaft 71, Fig. 8, and also Figs. 10 to 14. In the latter five of these drawings, the parts are viewed in elevation from the right-hand end of the machine. This clutch-release has an internal member 89 keyed to shaft 71 and a relatively movable outer ring 91 urged to rotate with the internal member by a coil spring 93 connecting the two parts. As shaft 71 is rotated counter-clockwise, a striker 95 on outer ring 91 engages a roller 97 on the end of an arm 99 fixed on rockshaft 51. This engagement arrests the striker and ring of the clutch-release, stressing the spring 93 as the internal member 89 continues its rotation with shaft 71.

As shaft 71 rotates, the rim of a notched counter 101, Figs. 10 and 13, fixed thereon holds a lever 103 fixed on rockshaft 51 in such position as to keep rockshaft 51 rocked and the collar 97 in position to arrest temporarily the travel of striker 95, the parts remaining in the relation of Figs. 10 and 12. But when shaft 71 completes its single rotation the end of lever 103 drops into a notch in counter 101, as shown in Fig. 13, which permits reverse rotation of rockshaft 51 in a counter-clockwise direction under the pressure of spring-impelled striker 95 on outer ring 91 of the delayed-action clutch, to allow arm 99 to move into its dotted line position of Fig. 12 and to permit striker 95 to slip by roller 97. As already noted, as this occurs, shaft 71 is completing its single revolution and counter 75 fixed thereon has turned into position to let dog 83 enter the notch in such counter, which lets lever 55 rise to engage the control-sleeve 53 of single revolution clutch 51 and thus terminate the driving of shaft 49 which rotates the turret and which also drives shaft 71.

The striker 95 as it snaps by roll 97 strikes a second roll 105 carried by an arm 107, Figs. 10 and 14, fixed on shaft 51 and pivotally connected to a link 109 which is in turn pivotally connected to the short arm 111 of a three-armed lever 113 freely rotating on a stud fixed in a stand 115 on shelf 29. When the blow of striker 95 forces roll 105 out of its path, the corresponding movement of arm 107 thrusts link 109 to the left, disengaging the straight right-hand end of lever 113 from a shoulder on the control-sleeve 117 of a second single revolution clutch 119 whose interior body is fixed on continuously driven shaft 33 driven through bevel gears 31, 39, from pulley-shaft 35. Release of this clutch 119 causes the driving of shaft 121 on which is a worm 123 en-

gaging with a worm gear 125 which is fixed on a sleeve 127, Fig. 3, rotating in a vertical bearing 129 fixed in sunken top panel 175 of the machine. This sleeve is provided with a pair of internal grooves in which work the splines of a short vertical shaft 131 having a head 133 which has a transverse tongue across its circular top face. Shaft 121, and shaft 49 also, contain couplings 50 having radially slotted interengaging faces enabling an axial shift of the two portions of each shaft connected together by these couplings, for the purpose of accurately timing the parts driven by these two shafts.

The splined shaft 131 constitutes the means for rotating the heel-blank on its vertical axis while within range of the cutting blades of the cutter. Thus, each of the plurality of heel-spindles comprises a turn-table 3, Figs. 5 and 6, keyed and secured by nut 135 to a vertical spindle 137 rotating freely in a vertical bearing 139 affixed by means of lugs 141 to seats on the vertical side wall of the bell of turret 4, one being located at each end of a diametrical line through the bell. As noted, it is contemplated to install spindles at four locations 90° apart about the axis of the turret, in cases where it is desired to perform a sanding operation on the heel after trimming, at a station located between the point where the heel-blank is trimmed by the knife and the point at the front of the machine where new heel-blanks are being put in place on the spindle. The fourth station, diametrically opposite the sanding station, affords the operator a chance to verify the setting of the heel on its supporting surface before the heel reaches the knife. A thrust-bearing 143 is interposed between the top of the housing 139 and turn-table 3 to assure free rotation of the turn-table while the heel is held firmly thereagainst by the presser mechanism.

To drive the heel-spindle from splined shaft 131, a collar 145 is pinned to the bottom end of spindle 137, and formed at its bottom surface with a deep diametrical slot to receive the correspondingly-shaped transverse tongue on head 133 on splined shaft 131. Thus, when these parts are clutched together in alignment, rotation of shaft 121 transmits rotation to heel-spindle 137 to revolve the heel-blank on its vertical axis while being trimmed.

To ensure the heel-spindles and the blanks borne thereby always arriving at their several stations in the same angular relation, thus insuring proper clutching of the shaft to the spindle, a circular track 147 is provided which completely encircles the base of the bell of the turret at the level of tongued head 133 of splined shaft 131, such track being interrupted adjacent head 133; on this track slides the slotted collar 145 of each heel-spindle, thus presenting the slotted collar in proper angular relation to slide into engaging and driving relation with the head of shaft 131 as each heel-spindle in turn is brought into working position in front of cutter 25 through rotation of turret 4.

After the heel-blank on its spindle arrives at its station in front of the knife, and commences to rotate on its vertical axis, one side of the heel-blank adjacent a corner formed by the breast-trimming operation is first presented to the action of the cutter 25; shaft 131 rotates slowly throughout a full turn, through the driving means described, to cause the cutter to trim the entire circuit of the heel around the sides and

back thereof until the cutter has reached the opposite corner of the breast of the heel.

To shape the heel in plan, relative motion of the vertical axis of the heel with respect to the orbit of the cutting edges of the knife 149 on cutter 25 must be provided, and this is accomplished in the present machine by moving the table 27 carrying cutter 25 and motor 23 toward and from the axis of rotation of the heel-blank, as already noted. This in-and-out travel of the cutter is attained by driving a secondary shaft 151 mounted in bearings close beside shaft 131 by means of interengaging spur gears 153, 155, respectively fixed on these two shafts, and by mounting on the top end of shaft 151 a cam 154 bearing against a plate 157, Fig. 2, adjustably fixed on table 27, the whole table being urged toward the turret by contracting coil springs 159 attached to the rear end of the table and anchored to the machine frame to cause the table to move toward and from the turret in accordance with the shape of cam 154. This cam is removably held on its shaft by a nut 161, so that it may be easily replaced by another cam of different shape when the shape of the heel is to be varied.

It is not necessary to change the cam to vary the size of the heel, as this is accomplished through adjustment of the position of plate 157 lengthwise of table 27. The plate slides in short tracks 162 hung from the under surface of the table, and has a downwardly extending lug on its under surface which is threaded and engaged with a screw thread on the end of a shaft 163 manually rotated by crank 165. When plate 157 is moved rearwardly with respect to table 27, away from the turret, it lets the cutter 25 approach nearer the turret and thus makes a smaller size of heel. A small pinion gear on screw-shaft 163 engages with a larger index gear alongside of it in housing 167 therefor, and an index dial is adjustably fixed to the face of this larger gear by thumb-screw 169, this index dial bearing graduations corresponding to the various established sizes of heels. Thus, with any random setting of the table by means of screw 163, a heel-blank is cut into the form of a finished heel, the size checked against the known standard, and the index set to indicate the size thus found. Thereafter, moving of the screw 163 in either direction until one of the size markings on the index dial corresponds with the pointer marked on the housing will give exactly the size of heel indicated by the dial. Hence, once the size resulting from any given position of the table is determined, the calibrated dial enables all other standard sizes to be obtained. Preferably the heel sizes are cut in succession from the largest to the smallest sizes, because the aluminum plate 5 forming the slanting heel-supporting surface of the turn-table is trimmed away in the process.

Unique forms of heels such as that shown in Figs. 19 and 20, having the usual rounded shape at the cupped end conforming to the outlines of the heel portion of the shoe, but with a polygonal shape in horizontal section at the tread end of the heel, and with the flattened areas incident to such polygonal shape fared off and blended smoothly into the rounded upper portions of the heel, can easily be made on the machine by first cutting the heel in usual shape by the use of the regular cam 154, Fig. 2, and then lowering the turret by means of adjusting screw 195, Fig. 3, and cutting the heel over again while the movement of the table is controlled by an appropri-

ately shaped cam such as 156, Fig. 18, substituted on shaft 151 for cam 154.

Table 27 runs on ball-bearing rollers 171, Fig. 7, mounted on shouldered pins 173 put through the side frame 31 of the machine and also through the flange of the depressed top panel 175 of the machine frame. The inward portions of these pins 173 are formed eccentric, and on these latter portions are rolls 177 which bear against tracks 179 fixed to the under side of table 27 whereby any tendency of the table to vibrate upwardly under the resistance met with by the cutter 25 can be counteracted through rotation of pins 173; after adjustment, these pins are locked by nuts 181. A third form of guiding means for the table, to prevent deviation in a horizontal plane, comprises rollers 183 on vertical studs fixed in the top panel 175 and bearing against a vertical surface on tracks 179, the studs for the rollers at one side of the machine being transversely adjustable by means of slots in the panel 175 to provide for taking up all transverse slack in the mounting of the table.

The reaction of the cutter upon impact of its blades against the heel-blank is effectually absorbed by the great weight of the table and its load of motor and cutter, aided by the two strong table-moving springs. A housing 184 around the cutter both guards the blades and catches the chips.

To give the heel its desired shape in profile, a change in the relative elevation of the heel-blank with respect to the axis of rotation of knives 149 on the cutter is utilized. That is, a change in the level at which the heel-blank is tangent to the orbit of the knives gives the back of the heel its customary sharper slope as regards the sides of the heel which is required in shaping the heels for women's shoes. This is accomplished herein by lifting and lowering the entire turret with its heel-spindles and the heel-blanks thereon as the working heel-spindle is rotated on its vertical axis. To do so, the turret 4 rotates on a similarly shaped guide 185, having a flanged bottom rim 187 firmly fixed on the sunken top panel 175 of the machine frame; the interior of the cylindrical upper portion of the turret slides and rotates freely on the correspondingly-shaped portion of this guide. Within the guide is a supporting shaft 189 having fixed on its upper end a collar 191 on which rests the bottom element of an anti-friction bearing 193 connected to the top end of turret 4 and carrying the weight of the turret with all its parts. Into the lower end of turret shaft 189 is threaded an adjusting screw 195, Fig. 3, having a knurled rim for manual adjustment, and having its head in contact with a shoulder on a bracket 197 which has a split sleeve 199 fitting around the foot of shaft 189 and clamped tightly in place thereon by cap-screw 201. This bracket carries a roll or cam-follower 203 which rests upon the periphery of a cam 205 whose rotation causes the lifting and lowering of the entire turret and thus of the heel-blank to present the latter to the cutter at the desired levels to effect this phase of the shaping of the heel. Adjustment of the levels throughout which the turret rises and falls under the action of cam 205, so as to change the style of the heel, is thus easily effected by loosening screw 201 and manipulating adjusting screw 195 so as to increase or diminish the effective length of turret shaft 189. This, combined with adjustment of the radius of the knife-edges on cutter 25, provides for a wide variation of the

profiles of the sides and rear of the heels thus cut. To guide the foot of turret shaft 189, bracket 197 has a slot 207 fitting over a small block 209 supported in fixed position from the under side of top panel 175, this block serving to hold bracket 197 against rotation and so that it moves in a fixed vertical plane, thus maintaining the foot of the shaft in vertical alignment over the axis of cam 205.

Cam 205 is mounted on a short countershaft 211 supported in suitable bearings from the under side of top panel 175, and having fixed thereon a spur gear 213, Fig. 8, driven by an equal spur gear 215 on a stub-shaft 217 on which is also fixed a worm gear 219 driven by a worm 221, Fig. 1, on the same shaft 217 which imparts the rotation to spline-shaft 131 rotating the heel-spindles. Thus the rise and fall of the turret is effected simultaneously with the rotation of the heel-blank about its vertical axis.

To stop these two motions of the heel-blank when the entire convex portions of the sides of the blank have been subjected to the action of the cutter, bevel gears 223, Fig. 8, respectively fixed on the ends of countershaft 211 and on a longitudinally extending countershaft 225, Fig. 8, drive the latter shaft to rotate a counter 227, whose full diameter periphery engages the toothed left-hand extremity of three-armed lever 113, Figs. 10 and 11, holding the straight right-hand end of such lever out of the path of the shoulder on control-ring 117 of clutch 119, (the lever having been rocked by striker 95 through link 109 as earlier described) until the notch in the rim of counter 227 completes a full rotation and again receives the toothed left-hand end of lever 113, whereupon the lever rocks reversely and its right-hand end engages the shoulder of control-ring 117, disengaging the clutch 119 and arresting the drive of shaft 121 and all the connected parts which lift and rotate the heel-blank and shift the cutter toward and from the axis of rotation of the heel-blank. This completes the working cycle of the machine on any given heel-blank and brings it to rest, and a fresh actuation of treadle 21 is necessary to begin the next cycle by rotating the turret.

To prevent a second and premature actuation of the treadle from throwing the timing out, shaft 11 carries a cam 229, Figs. 8 and 9, which is engaged by a follower in the form of a roll 231 on a yoke 233 having one end astride shaft 11 and its other end sliding in a guideway in connection with the frame of the machine, and beyond such guideway equipped with two pins 235 standing respectively at opposite sides of push-link 63 which is connected to starting treadle 21, the yoke being pressed against the cam by a coil spring 237. Thus, as soon as shaft 49 begins its rotation, the resulting rotation of shaft 11 causes cam 229 to thrust link 63 out of lifting engagement with shoulder 59 on starting lever 55, this inoperative relation of the link persisting until shaft 11 has completed its single turn, with the accompanying number of rotations of shaft 49 needed to bring the next heel-spindle on the turret into its next station. As noted, completion of the single rotation of shaft 11 initiates the rotation of shafts 121 and 225, and on the shaft is an additional counter 239, Figs. 8 and 9, which thereupon takes over the task of blocking a second actuation of lever 55 until the machine has completed its cycle.

To make the track 147, which orients the heel-spindles during their circuit around the turret,

follow the turret in the latter's rising and falling movement which gives the heel the desired profile on sides and back, a bracket 241, Figs. 3 and 4, is fixed upon non-rotating turret-lifting shaft 189 by means of a key and set screws through its hub which surrounds such shaft. Track 147 is supported on radial arms of this bracket, and thus the track follows the turret up and down to maintain a constant level with the slotted collars 145 comprising the bottom ends of the several heel-spindles. This track also serves to carry the splined shaft 131 up and down through sleeve 127, so as to keep the transverse tongue on its head end in driving engagement with the slot in bottom end 145 of the heel-spindle throughout the rise and fall of the turret. For this purpose, a yoke 243 of horseshoe shape in plan engages in a groove 245, Fig. 3, in the head 133 on the spline shaft, the yoke being attached by screws to the under side of the track at each side of the gap left therein for interengagement of the shaft head with the spindle bottom.

Pivot 13 for arm 11 on which the manually-operated locating gauge 9 is mounted, is also fixed in a lateral extension of bracket 241 supporting the track.

The track is continuous around its entire circuit except where interrupted for the head of spline shaft 131, so that each heel-spindle occupies a given angular position while waiting for reloading at the front of the machine throughout the operation of cutting the heel-blank on the alternate spindle.

As already noted, the primary support for the heel-blank in the machine is the aluminum plate 5 on which the cupped end of the blank is seated, either with or without the interposition of a sheet of paper 8, Fig. 15. This plate is fixed by a screw 10 and located by two points 12, intended to be embedded in the heel-blank, on top of a wedge block 14 which gives the desired angle to the cupped end of the heel, and which block is replaced by others of different inclination for different styles of heels, as shown in Fig. 17. This block 14 has a tongue on its under surface received in a corresponding slot in the top of the turn-table 3 of each heel-spindle, so that the heel will always start from the same relative angular position in being shaped, and the reduced and threaded top end of spindle 137 above nut 135 fits snugly in an unthreaded hole through the wedge block to prevent lateral escape. The breast-gauge 7 is screwed to the tall end of wedge block 14.

The presser mechanism which holds the heel-blank firmly in position on points 12 and plate 5 during the cutting, is shown in Fig. 1 and comprises a spindle 15 with a swiveling foot in ball-and-socket connection, the spindle being mounted to slide up and down and rotate freely in a sleeve 18 located above and in axial alignment with the axis of each heel-spindle in the outer end of a bracket 20 extending laterally from the cylindrical top portion of the turret. Each spindle 15 is pressed downward by a thumb-screw 22 which is also in ball-and-socket swiveling connection with the top end of its spindle, and capable of lifting the spindle upward away from the heel block for removal of the latter. The shank of the thumb screw passes through a split nut clamped together by a small transverse screw 24 to bind the thumb screw against unwanted rotation. This split nut is in turn swiveled on horizontal pintles in the forked end of a lever 26 pivoted in a bracket 28 extending up

from spindle bracket 20. The opposite end of this lever 26 is connected by a link 30 to an arm 32 fixed on a transverse rockshaft actuated by the handle 17, so that when the handle is pushed up the toggle-linkage composed of link 30 and arm 32 straightens and then passes beyond centers and thus locks the spindle in its downwardly extended relation in which it presses hard upon the upper or tread end of the heel-blank. A simple adjustment of thumb screw 22 for heels of different heights serves to allow the toggle to lock as the foot of the spindle exerts the desired downward pressure upon the heel-blank. Each presser thus put into clamping relation with a heel-blank at the right-hand end of the machine remains locked in clamping relation while the turret carries the particular heel-spindle and blank clamped thereon to and beyond the cutting position, and at any desired point in the circuit of the turret after leaving the vicinity of the cutter the high point of a cam 34 fixed on the top end of the turret shaft 189 presses the toggle reversely and the weight of handle 17 either alone or aided if necessary by an auxiliary spring, folds up the toggle joint and lifts spindle 15 to free the heel after removal and make way for the insertion of a new heel-blank when the spindle arrives at its station at the front of the machine. In practice, a simple striker 36 affixed to the side of track 147 and having a horizontal inwardly-extending finger in the path of the heels and just clearing the top of breast-gauge 7, occupies a stationary position to knock off the shaped heels from their spindles into a chute 38 so that each spindle arrives empty at its loading station.

Motor 23 is mounted on a plate 251, hinged to sliding table 27 at 253, and adjusted up or down by screw 255, to tighten V-belt 43 driving the mechanism.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but

What I do claim is:

1. A heel-shaping machine having a combination means supporting and rotating the heel, a cutter acting on the heel while thus supported and rotated about a fixed axis extending through the heel, and means guiding the supporting and rotating means toward and from the cutter in a circular path, the supporting and rotating means being arrested in its travel along such path while the cutter is acting on the heel.

2. A heel-shaping machine having in combination means supporting and rotating the heel, a cutter acting on the heel while thus supported and rotated about a fixed axis extending through the heel, and means carrying the supporting and rotating means toward and from the cutter in a fixed path, the carrying means being inactive to propel the heel along such path while the cutter is acting on the heel.

3. A heel-shaping machine having in combination means supporting and rotating the heel about a fixed axis passing through the heel, a cutter acting on the heel while thus supported and rotated, and means mounting the supporting and rotating means for rotation on an axis apart from that through the heel, rotation about

the two axes being effected alternately and not concurrently.

4. A heel-shaping machine having in combination a rotary cutter, devices supporting and rotating the heel on a fixed axis while being cut by the cutter, and means carrying the supporting devices to and from the cutter respectively before and after the cutting, but inactive during the cutting.

5. A heel-shaping machine having in combination devices supporting and rotating the heel on a fixed axis, means imparting movement to the heel along such axis, and a cutter cutting the heel while the latter is thus rotated and moved on the fixed axis.

6. A heel-shaping machine having in combination devices supporting and rotating the heel on a fixed axis, means imparting movement to the heel along such axis, and a cutter rotating on an axis at right angles to such axis cutting the heel while the latter is thus rotated and moved on the fixed axis.

7. A heel-shaping machine having in combination devices supporting and rotating the heel on an axis fixed in the machine frame and extending through the heel, a rotary cutter cutting the heel, and means moving the cutter bodily toward and from such axis during the cutting.

8. A heel-shaping machine having in combination a cutter, a plurality of devices for supporting heel-blanks with capacity for rotation, means carrying such devices successively past the cutter, and means rotating each heel-blank about a fixed axis passing through the heel-blank when presented to the cutter by the carrying means, the carrying means being inactive to propel the heel past the cutter during such presentation.

9. A heel-shaping machine having in combination a rotating carrier, a plurality of heel-supports rotatably mounted on such carrier in fixed equidistant relation from the axis of the carrier, a cutter to which each heel is presented in succession while on its support by the rotation of the carrier, and means for rotating each support about a fixed axis passing through its heel while its heel is presented to the cutter and while the carrier is at rest.

10. A heel-shaping machine according to claim 9 having means acting in timed relation with the rotation of the support shifting the cutter toward and from the latter support.

11. A heel-shaping machine having in combination a rotating carrier, a plurality of heel-supports rotatably mounted on such carrier in equidistant relation from the axis of the carrier, a cutter, and means automatically rotating the carrier to bring a support into proximity to the cutter, rotating the support in such location about a fixed axis coaxial with the support while the carrier is at rest, and simultaneously shifting the cutter toward and from the support.

12. A heel-shaping machine having in combination a driving element rotating on a fixed axis, a plurality of rotatable heel-supports, means bringing the supports successively into driving engagement with the driving element to

rotate each support in turn, and means shaping a heel on a support while thus rotated.

13. A heel-shaping machine having in combination a rotating turret, a plurality of heel-supports at spaced intervals about the axis of rotation of the turret and each rotatable about an axis parallel to the turret's axis, means automatically rotating the turret to bring each heel-support in succession into a predetermined position and thereupon to rotate the support on its axis, a cutter, a movable support for the cutter, means yieldingly moving the cutter's support and thus the cutter toward the axis of the rotating heel-support, and cam means actuated in timed relation to the rotation of the heel-support upon its axis, controlling the spaced relation of the cutter with respect to the axis of the rotating heel-support.

14. A heel-shaping mechanism having in combination a rotating turret, a plurality of heel-supports at spaced intervals about the axis of rotation of the turret and each rotatable about an axis parallel to the turret's axis, means automatically rotating the turret to bring each heel-support in succession into a predetermined position and thereupon to rotate the support on its axis, a cutter, a movable support for the cutter carrying the cutter toward and from the axis of the heel-support in timed relation to the rotation thereof, and cam means lifting and lowering the turret in timed relation to the rotation of the heel-support on its axis.

15. A heel-shaping machine having in combination a rotating heel-support, means pressing the heel downwardly against such support, means trimming a heel held on such support, devices conveying the rotating heel-support and the heel held thereon to and from the trimming means, and means automatically lifting the pressing means and thus releasing the trimmed heel from the heel-support after trimming.

16. A heel-shaping member having in combination, a cutter, a rotatable support presenting the heel to the cutter, devices moving the support and thus the heel along the axis of rotation of the support while the cutter is working on the heel, and manually adjustable means varying the movement of the heel by such devices and thus varying the shape given to the heel by the cutter.

17. A heel-shaping machine having in combination heel-trimming means, heel-supporting means, carrying means transporting the heel-supporting means to and from the trimming means, power devices propelling the carrying means, control means worked by the operator of the machine setting the power devices in action to propel the carrying means till the heel-supporting means is presented to the trimming means, other power devices rotating the heel-supporting means and set in action when the heel-supporting means is thus presented to the trimming means, and safety devices preventing the control means from again setting the first power devices in action to shift the carrying means until the rotating movement of the heel-supporting means is completed.

CLAYTON STRAW.
